TOY TELEPHONE

Harry Bregman, Lorain, Ohio, assignor to The Steel Stamping Company, Lorain, Ohio, a corporation of Ohio

Application May 16, 1935, Serial No. 21,720

18 Claims. (Cl. 46—33)

This invention relates to toy telephones, and more particularly to a toy telephone of the type having a calling device such as a rotatable "dial".

An object of the present invention is to provide an improved toy telephone having a calling device and novel signaling means arranged to be actuated by the calling device.

Another object of the invention is to provide a toy telephone of the "dial" type having novel signaling means including a plurality of sound producing devices arranged to be actuated by rotation of the dial.

Still another object of the invention is to provide an improved toy telephone of the type having a rotatable dial and signaling devices including a bell adapted to be actuated in response to rotation of the dial in one direction, and a voice simulating device adapted to be actuated in response to rotation of the dial in the opposite direction.

A further object of the invention is to provide an improved toy telephone having a dial and a signaling device, and novel means for operatively connecting the dial and the signaling device.

Other objects and advantages of the invention will be apparent from the following description when taken in conjunction with the accompanying sheet of drawings, wherein

Fig. 1 is a side elevation of a toy telephone embodying my invention.

Fig. 2 is a plan view thereof.

Fig. 3 is a transverse sectional elevation taken on line 3—3 of Fig. 1.

Fig. 4 is a partial sectional plan view taken as indicated by the irregular section line 4—4 of Fig. 3.

Fig. 5 is a fragmentary view showing the dial and bell ringing mechanism, and

Fig. 6 is a similar view showing the dial and bell ringing mechanism in section.

More detailed reference will now be made to the accompanying drawing for the purpose of describing the improved toy telephone which embodies my invention. However, before proceeding with such detailed description, it should be understood that the invention is not necessarily confined to the particular construction illustrated, but may be embodied in various other devices coming within the scope of the appended claims.

My invention may be embodied in a toy telephone of the cradle type, that is to say of the type having a standard or base and a combined transmitter and receiver removably supported

thereon, and in Figs. 1 and 2 of the drawing I show a telephone of this type. The base 10 of this telephone may comprise a sheet metal shell 11 which has been stamped or otherwise formed to the desired shape, and a cradle 12 thereon which provides a support for the combined transmitting and receiving hand set 13. The base may also include a bottom cover plate 14 which may, if desired, be provided with a covering or sheath 15 of felt or other suitable material.

The hand set 13 may be of any suitable construction, such as sheet metal, and may comprise a handle part 17 having receiver and transmitting parts 18 and 19 secured to opposite ends thereof. The handle part 17 is shaped for removable supporting engagement in the cradle 12. A cord 20, simulating an electric conductor cord, may be arranged to connect the hand set 13 with the base 10.

The cradle 12 and the bottom cover 14 may be conveniently secured to the shell 11 by means of a clamping rod or bolt 22 which extends downwardly through the cradle and the shell and has a clamping nut 23 disposed in a recess of the bottom cover 14. The cradle may be spaced 25 above the shell 11 of the base by means of a spacer 24, of wood or other suitable material, through which the clamping rod 22 extends.

As shown in Fig. 3 of the drawing, the shell 11 of the base may be provided in the front 30 wall thereof with a recess 25 in which the rotatable dial 26 of the calling device is arranged. The calling device also includes a plate 27 having an annular series of numerals or characters such as the names of cities or stations. As is 35 usual in devices of this kind, the rotatable dial 26 has an annular series of openings 28 through which the characters are visible. The openings of the dial are shaped to receive a child's finger for causing rotation of the dial.

In accordance with my invention I provide this improved telephone with a plurality of signaling devices 30 and 31 which, as will be presently explained, are arranged to be actuated in response to rotation of the dial 26. The signaling device 30 comprises a bell 36 and mechanism for ringing the same. The signaling device 31 may be a voice simulating device such as a device capable of producing a cry or squawk.

The dial 26 is mounted upon a rotatable shaft 33 and is drivingly connected thereto by means of the nut 34 cooperating with the shoulder 35. The shaft 33 extends into the hollow shell 11 and, at its inner end, carries the bell 36 and a winding member 37. The bell and the winding member 55

may be secured to the shaft by nuts 38 and 39 so that these members will be rotated with the shaft. A coil spring 40 may be disposed around the shaft 33 with one end thereof anchored to the shell 11 as indicated at 41, and its other end extending into an anchor slot or opening 42 of the shaft. A star wheel 43 and a ratchet wheel 44 are connected with each other and are both rotatably mounted on the shaft 33. The star wheel cooperates with an escapement-like pawl 45 to cause swinging movement of a bell clapper 46. The escapement-like pawl 45 is rockably mounted on a pivot 45a so that spaced portions thereof are alternately engaged by the teeth of the star wheel 43, and includes an integral offset arm 45b having the clapper 46 at its outer end. A plate detent 47 rotates with the shaft 33 and has spring fingers 48 adapted to engage the teeth of the ratchet wheel 44.

From the arrangement just described it will be seen that when the dial 26 is rotated in a clockwise direction the shaft 33 will rotate the plate detent 47 in the same direction, and the spring fingers 48 of the latter engaging the teeth of the ratchet wheel 44, will also cause the ratchet wheel and the star wheel to be rotated in a clockwise direction. This rotation of the star wheel 43 causes the clapper 46 to be swung or vibrated into striking engagement with the bell 36. The clockwise rotation of the shaft 33 tensions the spring 40 and, when the dial is released after the clockwise rotation, the spring rotates the dial in a counter-clockwise direction and returns the same to its starting position. During this return movement of the dial under the influence of the spring 40, the spring fingers 48 of the plate detent 47 ride over the teeth of the ratchet wheel 44 so that the star wheel 43 will not be rotated at this time.

The signaling device 31 may be a device of the type having a bellows 50 and a reed or other sound producing element (not shown) past which air is caused to flow by operation of the bellows. The device may be of the type having a weighted part 51 which is lifted to expand the bellows and which descends by gravity to collapse the bellows and force air past the sound producing element.

In accordance with my invention I transmit motion from the dial shaft 33 to the signaling device 31 to cause the bellows to be extended and collapsed in response to rotation of the dial. For this purpose I provide an operating connection between the dial shaft and the weighted part 51, preferably in the form of a cord or strand 53, which is connected with the weighted part and with the winding member 37. The strand may be led through one or more guide arms 54 which are suitably arranged to direct the movements of the strand.

With the arrangement just explained it will be seen that when the dial is rotated in the clockwise direction which, as explained above, produces ringing of the bell 36, the strand 53 is wound in the space 55 between the member 37 and the bell 36. The winding of the strand tensions the same and causes the weighted part 51 to be lifted to extend the bellows 50. When the dial is released and rotated in the counter-clockwise direction under the influence of the spring 40, the strand 53 is allowed to unwind and the weight 51 descends by gravity thereby collapsing the bellows 50 and forcing air past the sound producing element to cause the same to emit a cry or squawk which, in some instances, may be a sound simulating the voice.

As a feature of my invention, I may utilize an elastic strand as the strand 53 which provides the operating connection between the dial and the sound producing device 31. When an elastic strand is used for this purpose it will be seen that the strand need not be of an accurately determined length and the tensioning of the strand to lift the weighted part 51 may be caused in part by a winding up of the strand and in part by a stretching thereof. By use of such an elastic strand, operation of the signaling device 31 may be had as the result of either partial or complete rotary movements of the dial 26.

To facilitate assembly of the parts of the toy telephone I may provide a suitably shaped bracket 56 for supporting and positioning the signaling device 31. This bracket may be secured to the rear wall of the shell 11, as by means of rivets 57, and may have an arm 58 extending laterally above the bottom cover plate 14 for supporting the device 31. The arm 58 may have spring fingers 59 which grippingly engage the device 31 to retain the same in position. If desired, the bracket 56 may be extended upwardly so that the guide arms 54 may be carried thereby. The connection between the strand 53 and the weighted part 51 of the signaling device 31 is preferably located eccentrically with respect to the center 59' of the signaling device, as shown in Fig. 4, so that after the signaling devices 30 and 31 have been assembled into the base of the telephone in the relative positions shown in Fig. 3 and with the ends of the cord 53 connected thereto, it is only necessary to rotate the device 31 within the spring fingers 59 to take up any slack which may exist in the strand 53 when the dial is in its starting position. After the slack has been taken up the fingers 59 can be further deflected into firm holding engagement with the device 31.

The shell of the base 10 may be provided with a plurality of appropriate openings 60 for the passage of sound waves emanating from the signaling devices 30 and 31.

From the accompanying drawing and the foregoing description, it will now be readily understood that I have provided an improved toy telephone embodying a plurality of signaling devices arranged to operate in response to movements of the dial. It will also be seen that I have provided novel means for causing the desired operation of the signaling devices whereby one device, such as a bell, may be operated in response to rotation of the dial in one direction and another device simulating a voice may be operated in response to rotation of the dial in the opposite direction.

While I have illustrated and described the improved toy telephone of my invention in a somewhat detailed manner, it will be understood, of course, that I do not wish to be limited to the precise arrangements and details of construction illustrated and described, but regard my invention as including such changes and modifications as do not constitute a departure from the spirit of the invention and the scope of the appended claims.

Having thus described my invention, I claim:

1. A toy telephone of the dial type having a rotatable dial, a plurality of signaling devices cooperatively disposed relative to the dial, and operative connections between said dial and signaling devices arranged to cause operation of one signal device in response to rotation of the dial in one direction and operation of another signal device in response to rotation of the dial in the opposite direction.

- device in response to rotation of the dial in the opposite direction.
2. In a toy telephone, a base, and a calling device including a series of indicia associated with the base and a rotatable member mounted over said indicia, a plurality of signaling devices, means responsive to rotation of the rotatable member in one direction for actuating one signaling device, and means responsive to rotation of the rotatable member in the opposite direction for actuating another signaling device.
3. In a toy telephone of the dial type, a base, a calling device thereon including a rotatable dial member, a plurality of signaling devices including a bell ringing device and a voice simulating device, and operating connections rendering the bell ringing device responsive to rotation of the dial member in one direction and the voice simulating device responsive to rotation of the dial member in the opposite direction.
4. In a toy telephone, a hollow base, a rotatable member thereon, a plurality of signaling devices in said hollow base including a bell ringing device and a voice simulating device, said hollow base having sound exit openings, means for causing operation of the bell ringing device during rotation of said member in one direction, and means for causing operation of the voice simulating device during rotation of said member in the opposite direction.
5. In a toy telephone, the combination of a base, a rotatable member thereon, a sound producing device of the type having a bellows, and operating means responsive to rotation of said member for extending and collapsing said bellows, said operating means including a winding device driven from said rotatable member and a strand having connection with the bellows and adapted to be tensioned by rotation of said winding device.
6. In a toy telephone, the combination of a base, a rotatable member thereon, a sound producing device, and means for actuating the sound device including a winding device driven by said rotatable member and a strand having connection with said sound device and adapted to be tensioned in response to rotation of said winding device.
7. In a toy telephone, the combination of a base, a rotatable member thereon, a sound producing device, means for actuating the sound device including an elastic strand adapted to be tensioned by rotation of said member.
8. In a toy telephone, the combination of a base, a rotatable member thereon, a signaling device, means responsive to rotation of said member for actuating said signaling device, a sound producing device, and means for actuating the sound device including a rotatable winding means operatively associated with said rotatable member and a strand adapted to be tensioned by rotation of said winding means.
9. In a toy telephone, the combination of a base, a rotatable member thereon, a signaling device, means responsive to rotation of said member for actuating said signaling device, a sound producing device of the type having a bellows and means for collapsing the same, a winding means adapted to be operated by said rotatable member, and a strand having operative connection with said bellows and adapted to be tensioned by said winding means to extend the bellows in response to rotation of said member.
10. In a toy telephone, the combination of a base, a rotatable member thereon, a signaling device, means responsive to rotation of said member for actuating the signaling device, a sound producing device of the type having a bellows and means for collapsing the same, a winding means adapted to be tensioned by said rotatable member, and a strand connecting the bellows with said winding means and adapted to be tensioned by the latter.
11. In a toy telephone, the combination of a base, a dial thereon adapted to be rotated manually in one direction, a spring for rotating said dial in the opposite direction, said spring being arranged to be tensioned during the manual rotation, a signaling device, means responsive to the manual rotation of said dial for actuating said signal device, a sound producing device of the type having a bellows and means for collapsing the bellows, and means responsive to the manual rotation of said dial for extending the bellows.
12. In a toy telephone the combination of a base having a rotatable dial thereon, a signaling device, means mounting said signaling device on said base so as to permit rotation of the device relative to the base, and means for actuating said signaling device in response to rotation of the dial including a strand having connection with the signaling device eccentric to its axis of rotation whereby rotary adjustment of the signaling device takes up slack in the strand.
13. In a toy telephone, a base, a plurality of sound emitting signal devices thereon, a manually operable spring-returned dial, and connections between the dial and the signal devices operable to cause sequential sounding of said devices.
14. In a toy telephone, the combination of a base having a bell device and a pneumatic device thereon, a rotary actuating member movable manually in one direction, a spring adapted to move the actuating member in the opposite direction, means connecting the pneumatic device for operation by said actuating member, and a ratchet mechanism operably connecting the actuating member and said bell device.
15. In a toy telephone, a base having thereon a bell device and a pneumatic device, a manually operable spring-returned dial, and a ratchet mechanism and an elastic cord providing respectively an operating connection between the dial and said bell device and between the dial and said pneumatic device, said ratchet mechanism and elastic cord cooperating to cause sequential sounding of said devices.
16. In a toy telephone, the combination of a base having thereon a pair of sound producing devices one of which is a pneumatic device, a rotatable operating member manually movable in one direction, a spring adapted to cause return movement of said operating member, means connecting said operating member and said pneumatic device to cause sounding of the latter during said return movement, and a ratchet mechanism between said operating member and the other signal device for causing sounding of the latter during said manual movement.
17. In a toy telephone, a base having thereon a bell device and a pneumatic device, a pivoted actuating member manually movable in one direction and adapted to be automatically returned, means operably connecting said actuating member and said pneumatic device including an elastic strand adapted to be tensioned and stretched during manual movement of said actuating member and to be contracted and slackened during return movement of the actuating member.

and a ratchet mechanism for causing operation of the bell device during manual movement of the actuating member and rendering the bell device inoperative during said return movement of the actuating member.

5. 18. In a toy telephone, a base having a pneumatic sound producing device thereon, a pivoted actuating member selectively movable manually through different angular distances and

adapted to be automatically returned, and an operating connection between said actuating member and said device comprising an elastic strand adapted to be tensioned and stretched during manual movement of the actuating member and to be contracted and slackened during the return movement of the actuating member. 5

HARRY BREGMAN.
